UNITED STATES PATENT OFFICE.

JOSEPH W. ROBBINS, OF WILTON, NEW HAMPSHIRE.

BOX-COVER PRESS.

Application filed November 15, 1922. Serial No. 601,104.

To all whom it may concern:

Be it known that I, JOSEPH W. ROBBINS, a citizen of the United States, residing at Wilton, in the county of Hillsborough and State 5 of New Hampshire, have invented certain new and useful Improvements in Box-Cover Presses, of which the following is a specification.

This invention has reference to box cover 10 presses and its object is to provide a device whereby a box cover may be subjected to pressure to hold it positively in position on the box during the nailing of the cover thereon.

15 In accordance with the invention, there is provided a support for the box to be nailed, with a movable follower operating to clamp the box cover in position, with the mechanism for so holding the box cover operating 20 on the toggle principle to positively lock the parts while the nailing is proceeding, whereupon the holding or locking mechanism may be released and returned by the action of a spring to the unlocked position.

25 The mechanism employed for locking the cover on the box during the nailing procedure, is of extreme simplicity and yet is positive in action.

The invention will be best understood 30 from a consideration of the following detailed description taken in connection with the accompanying drawings forming part of this specification, with the understanding however that the invention is not confined to 35 any strict conformity with the showing of the drawings but may be changed and modified so long as such changes and modifications mark no material departure from the salient features of the invention as expressed 40 in the appended claims.

In the drawings forming part of this specification;

45 Figure 1 is a side elevation of the mechanism for supporting and clamping the box in position, but with the clamp structure in the unlocked condition.

Fig. 2 is a view similar to the showing of Fig. 1, but with the clamping structure in the locked position holding the cover in condition to be nailed.

Fig. 3 is a front elevation of the device showing the cover in the clamped position.

Figs. 4, 5 and 6 are separate views of parts of the clamping structure.

55 Referring to the drawings, there is shown

a work support 1 which may be conveniently in the form of a trestle provided with pairs of upright guides 2 at opposite ends with the guides appropriately spaced apart to receive between each of them a slide member 3 60 of appropriate length. These slide members are joined by cross members 4, 5 and 6, respectively, the member 5 serving as a support for a box or container 7 designed to contain fruit or vegetables, while the cross piece 65 4 joins and participates in the movement of the slides 3.

The cross pieces 4 and 5 are joined by a coiled spring 8 tending to cause the slides 3 to rise under the contractive action of the 70 spring 8.

The cross piece 6 carries a follower 9 designed to bear upon and force a cover member 10 into engagement with the box or container 7 to be held against the top of the box 75 7 during the nailing operation.

There are two slides 3 provided, one on each side of the structure between the respective pairs of guides 2.

Connected to each slide 3 on opposite sides 80 of the structure is a toggle member made up of two joined links 10^a, 11, the link 10^a being connected to the guide member 2 on one side of the slide 3 by a pivot pin 12, while the link 11 is connected at one end by a pivot 85 pin 13 to the lower end of the slide 3 and to the adjacent end of the link 10.

The link 10^a is overridden at one end by an offset extension 14 of the link 10^a which extension has an angular continuation 15 terminating a pin 16 adapted to pass through a slot 17 in the terminal portion 18 of a yoke 19 having a junction portion 20 of sufficient length to extend from one side of the structure to the other and shaped to constitute a 95 foot rest for the manipulation of the toggle members 10, 11.

Applied to the terminal portions 18 of the foot rest 20 are clips 21 each provided with a perforation 22 to pass a bolt 23 also passing through a perforation 24 at the angle junction of the continuation 15 with the link 10^a so that movement of the yoke 20 will cause an alinement of the toggle links 10^a, 11, or a breaking thereof in accordance with 100 the direction of movement of the yoke 20 thereby straightening or locking the toggle or loosening the toggle to the action of the spring 8 as the case may be, the bolts 23 105 causing a participation of the toggle in the 110

movement of the foot treadle 20 or with the spring 8 as the case may be.

The trestle structure 1 may either follow the usual construction of trestles or may be otherwise formed to answer the same purpose, that is to support and hold the box 7 to which the cover is to be nailed fast when held in place by the follower 6.

When the box is mounted on top of the 10 trestle and the follower 6 is brought into contact with the cover 10 of the box, the structures are firmly united and the nailing of the cover in place may proceed, after which the yoke structure 20 is raised there- 15 by breaking the toggle connection 10^a, 11, and allowing the spring 8 to act to raise the slide 3 and elevate the follower 6 automatically.

The action of the box clamping structure 20 may be rapid and certain, with the follower 6 locking in the depressed position and the toggle holding the follower during the process of nailing the box cover.

What is claimed is:—

1. A box cover press comprising a support for the box, slides on opposite sides of the support, pairs of guides outside of the support, with a slide between each pair of guides, a follower connected to and participating in the movements of the slides, 30 and a toggle actuator for the slides.

2. A box cover press comprising a support for the box, slides on opposite sides of the support, pairs of guides outside of the support, with a slide between each pair of 35 guides, a follower connected to and participating in the movements of the slides, and a toggle actuator for the slides, said guides and follower having associated with them an extension spring tending to hold 40 the toggle actuator in the extended or locked position.

In testimony whereof, I affix my signature hereto.

JOSEPH W. ROBBINS.
